PACKING MATERIAL

William J. De Reamer, Crown Point, Ind., assignor
to Mapes Consolidated Manufacturing Company,
Griffith, Ind., a corporation of Delaware

Application June 7, 1939, Serial No. 277,779

2 Claims. (Cl. 217—26.5)

This invention relates to improvements in packing material and it consists of the matters hereinafter described and more particularly pointed out in the appended claims. The packing material illustrated and described herein is especially adapted for use in connection with so-called cellular fillers for packing eggs in a conventional egg case.

The conventional egg case of commerce is generally made to standard dimensions and takes the form of an open top box with a transverse partition dividing the case into two compartments each substantially 12½ inches deep and 11½ inches square. Each compartment is adapted to hold 15 dozen eggs arranged in five tiers or layers of 3 dozen each and whereby the case has a capacity of 30 dozen eggs with an average weight of about 52 lbs. Such a packed case usually includes a cover for the open top thereof and which cover is nailed at its ends to the ends of the case.

Heretofore it has been the practice to provide a specially constructed pad for both the top and bottom of each compartment, to protect the eggs in the associated layers, in connection with different types of pads for the intermediate layers of eggs. As an example of the pads used at the top and bottom of each compartment, reference is made to my prior Patent 1,954,586 of April 10, 1934, and as an example of the intermediate pads, reference is made to the Koppelman and Cooper Patent 1,429,207 of September 12, 1922.

With an egg case packed with the patented pads above mentioned, the packer is required to stock two different types of pads and in such a packed case, the weight of the eggs, pads and cellular fillers is all imposed upon the bottom pad. Therefore, this pad had to be made relatively deep, "thick" or of such vertical dimensions as to make it support the weight of the eggs, pads and fillers above, without crushing. The pad of my prior patent functioned ably in this respect. However, its vertical dimensions are such as to prohibit its use between the several layers or tiers of eggs throughout the case because they would make the top layer of eggs so project above the top of the case as to prevent the application of the usual cover.

One of the objects of the present invention is to provide a packing material in the form of a cushion pad having seats each including a group of hollow upstanding projections so formed as to provide an area of contact conforming to associated parts of the egg to engage upon each seat and whereby the egg is not so apt to tip from its desired position upon the seat.

Another object of the invention is to provide a packing material of this kind and wherein the hollow projections forming the seats are not only formed for a better engagement by an egg but

have a greater resistance to crushing under the load imposed thereupon.

Again, it is an object of the invention to provide a packing material which can be used throughout the case from top to bottom and which is symmetrical about its four sides so that there is no necessity to dispose a certain side thereof in a definite relation with respect to any particular side of the egg case compartment in which it is used.

The above mentioned objects of the invention as well as others, together with the advantages thereof will more fully appear as the specification proceeds.

In the drawings:

Fig. 1 is a plan view on a full size scale of the egg receiving side of a quarter corner fragment of the improved pad, a part of the cell forming filler used therewith appearing in dotted lines thereon.

Fig. 2 is a detail full size vertical sectional view through the pad fragment shown in Fig. 1, the plane of the section being taken through the egg receiving seats thereof as indicated by the line 2—2 of Fig. 1.

Fig. 3 is another full size vertical sectional view through the pad fragment appearing in Fig. 1, as taken on the line 3—3 thereof.

Fig. 4 is also a full size vertical sectional view through the pad fragment as taken on the line 4—4 of Fig. 1.

Fig. 5 is a view in side elevation of an egg case packed with the improved pads and associated fillers, a part of the side of the case being broken away better to disclose the invention.

Fig. 6 is a vertical sectional view through one end of the packed egg case, before the cover has been applied and illustrates more particularly the "overage" or excess in height of the stack of pads and fillers over the depth of the egg case compartment containing the stack.

Fig. 7 is a view similar to Fig. 6 and shows the stack as having yielded in height to approximate the depth of the associated compartment as when the associated end of the cover has been nailed in position to close said compartment.

Fig. 8 is a vertical sectional view through the top portion of one end of the case with its cover in its closed position and shows the topmost pad in the stack as reversed face-for-face to arrange the egg receiving side of the pad downward.

The improved packing material in this instance is illustrated as employed in connection with standard unitary cellular fillers in a standard egg case. Such a case, which is indicated as a whole at 10, in Fig. 5, is generally made of wood veneer and cleats, to include sides 11, ends 12, a bottom 13, and a central transverse partition 14 which divides the case into two open top compartments. A cover 15 is included as a part

of the case and said cover, when it is nailed at its ends to the ends 12 of the case, closes the open top ends of the compartments. Ordinarily such a cover is not nailed to the transverse partition and therefore it takes on a slight bow as appears in Fig. 1.

The compartments of the egg case have a standard dimension, being approximately 12½ inches deep and about 11½ inches square.

The cellular fillers employed are of the standard unitary, folding, interlocking strip type. Each unit comprises two sets of seven strips each and which strips are indicated at 16. These strips are all of the same length and height and approximate 11½ inches in length and 2¼ inches in height. When said units are opened up into cellular form, they each provide 36 egg receiving cells each approximately 1¼ inches square. Five of such cellular fillers are employed in each compartment of the case so that each compartment holds 15 dozen eggs, giving a capacity of 30 dozen of eggs for the case.

17 indicates as a whole, one of the improved cushion pads, there being six of such pads used in each egg case compartment or twelve to the case. Such pads are arranged one on the bottom, one on the top and four intermediate the fillers 16 to coat therewith in forming a stack of packed tiers.

Each pad 17 which is a scant 11½ inches square, is preferably made of a molded pulp. It includes a sheet-like body portion 18 with a depressed margin 19 extending about the four sides of the pad and connected thereto by a downwardly and outwardly inclined wall 20, the corners of said margin being rounded as shown. The angle of inclination of the wall 20 is such that it easily releases from the mold in which the pad is made. The sheet-like body portion and the margin are each $\frac{1}{8}$ of an inch thick and the top surface of the body portion is spaced approximately $\frac{1}{4}$ of an inch above the bottom surface of the margin 19 as appears from the dimensions given on Fig. 2. With the dimension given it is apparent that the top surface of the sheet-like body portion is $\frac{1}{8}$ of an inch higher than the top surface of the margin 19.

In the marginal part of the four sides of the sheet-like body portion 18 are substantially semi-circular recesses 21 spaced equal distances apart and in each corner of the sheet-like body portion is a quarter circular recess 22.

Within the sheet-like body portion, in longitudinal and transverse rows, arranged in line with the recesses 21, are depressions 23. Each depression 23 has a downwardly and inwardly tapering annular side wall 24 and a flat bottom 25, the latter being disposed in the plane of the margin 19. The side wall 24 of said recess has substantially the same angle of inclination as the wall 20 before mentioned.

The depressions 23 are spaced apart in both directions of the pad, on centers 1¾ inches apart and which centers correspond to the distance between the intersections of the strips 16 of the associated filler when the same is in its open or expanded condition as will later appear.

Rising from top side of the sheet-like body portion and arranged in longitudinal and transverse rows thereon are egg receiving seats 26 arranged between the rows of depressions 23 in both directions of the pad. Each seat in this instance includes a relatively shallow circular platform, that comprises an upwardly and inwardly inclined annular wall 27 and a top wall 28, the

wall 27 having the same angle of inclination as the side wall 24 of the depressions 23 and into which parts of the walls 27 merge so as to form continuations thereof. The lines of emergence of said walls are disposed in planes extending diagonally of the pad on lines passing through the center of adjacent seats and depressions. Preferably the top surface of the wall 28 is spaced $\frac{1}{16}$ of an inch above the top surface of the sheet-like body portion 18.

Disposed about the margin of the top wall 28 above mentioned, is a group of upwardly projecting article engaging supports 29 spaced an equal distance apart from the center of the top wall 28. Each projection is substantially in the form of a rounded top circular dome and each projection is so formed in that side disposed in a plane radiating from the center of the top wall, as to provide an area of contact 30 for the egg to engage thereupon. With an egg, the end thereof may be considered as a part of a sphere and therefore such areas 30 are made as concavities conforming to those areas of the end of the egg that engages upon the same.

That part of the top wall 28 of each seat, between said projections 29 is concaved as at 31 to conform to the above mentioned part of the sphere and therefore said areas 30 are made as continuations of said concaved part 31 of the wall 28. As shown herein the projections or supports 29 are four in number and are of such diameter and are so disposed on the top wall 28 that those parts of the projections are supports opposite the areas 30 merge into and form continuations of parts of the side walls 27 of the seat as a whole. The top surface of the wall 28 of each seat is preferably spaced $\frac{1}{16}$ of an inch above the top surface of the body portion 18 and the top of each projection 29 rises $\frac{1}{16}$ of an inch above the top surface of the wall 28 so as to be disposed $\frac{1}{8}$ of an inch above the top surface of the body portion.

As before mentioned, the centers of the projection 23 are spaced apart to accord with the spacing between the strips 16 of the cellular fillers employed therewith and when each unit is opened up into cellular form and is positioned upon an associated pad 17, the intersections of the strips are positioned axially of the projections 23 and the semi-circular and quarter circular recesses 21—22, with an egg seat constructed as before mentioned, arranged within each cell as best appears in Fig. 1.

In packing a case 10 with the improved cushion pads, in connection with the standard or conventional fillers before mentioned, a pad is placed in the bottom of the compartment of the case, one on each side of the partition 14 with the egg receiving side up. The areas of contact between the pad and the bottom of each compartment then will be that area as defined by the margin 19 and bottom of the projections 23. As the arrangement of the seats and the projections is symmetrical, so as to be the same along all four sides of the pad, no care need be taken to place the pad in the compartment with a particular margin arranged with respect to a particular side of the associated compartment.

A cellular filler is then expanded or opened up into its rectangular cell forming condition and placed within each compartment so that its bottom edge rests upon the top surface of the body portion 18 of the first pads placed in the compartments. With the fillers arranged in this manner, each cell formed by the strips thereof

surrounds a seat that is located centrally of the cell. An egg is then placed, preferably with the small end down, in each cell. The egg will then engage upon the areas 30 of the projections 29 of the associated seat and the tip end of the egg will be spaced slightly from the central concaved portion 31 of the wall 28 when the egg is a relatively large one. When the cells have each received an egg, the first tier or layer in the compartment is constituted.

Another pad is placed in each compartment upon the top end edges of the first applied filler, at which time the bottom 25 of the projections 23 engage directly upon the intersecting portions of the strips 16. Thereafter, another film is arranged in position in each compartment upon the second pad therein and which fillers receive the eggs in the cells thereof, to form the second tier or layer of the stack being built up in each compartment.

The third, fourth and fifth tiers or layers are built up in each compartment and a pad is then placed upon the topmost filler in each of said compartments. If the eggs are of the ordinary size, the last pad applied is placed in position with the egg receiving side up. This provides in each compartment a stack of filled tiers or layers in each compartment, each comprising six top, bottom and intermediate pads and five alternate cellular fillers. As the first five pads have an effective depth equal to that of the distance between the bottom surface of the projections 23 and the top surface of the sheet-like body and which distance is $\frac{1}{4}$ of an inch and as the sixth one has an effective depth equal to the height of its projections which is $\frac{5}{8}$ of an inch and as each of the five filler strips has a depth of $2\frac{1}{4}$ inches, the effective height of the stack is the total of five times $\frac{1}{4}$ of an inch, plus five times $2\frac{1}{4}$ inches plus 1 times $\frac{5}{8}$ inch which makes $13\frac{1}{8}$ inches for the height of the stack overall.

As the compartments in which these stacks are arranged have a depth of $12\frac{1}{2}$ inches, as before mentioned, it is apparent that the stack projects above the top of the case the difference between $13\frac{1}{8}$ inches and $12\frac{1}{2}$ inches or $\frac{5}{8}$ of an inch before the cover is applied to the case to close the compartments.

This means that there is an "overage" in height between the height of the stack and the depth of the compartment in which it is located and which "overage" must be taken up when the lid or cover for the case is applied thereto. The lid or cover is attached by driving nails through the ends thereof into the ends of the case so that the cover bows slightly at its middle to be spaced above the top of the partition 14 of the case.

When the cover is brought home into compartment closing position, on the case, a compression force is applied to each stack, which is absorbed by the egg spacing material in the various pads.

When relatively large eggs constitute the majority of the eggs packed in said compartments, the topmost pad is placed in said compartments, with the seats thereof facing upwardly, which is in the same direction as the seats in the other five pads below, as shown in Fig. 6.

However, when the eggs in the top layer are relatively small, if desired, the pad at the top of the stack may be reversed to face the seats down-

wardly so that the areas 30 of the seats come substantially close to the top ends of the eggs in the top layer. When the top pad has been reversed, this reduces the height of the stack a distance equal to the height which the projections 29 extend above the top surface of the sheet-like body portion and which in this instance is $\frac{5}{8}$ of an inch.

The improved construction eliminates the necessity of the use of more than one kind of pad in a case. It does not require a new mode of manipulation in packing or unpacking an egg case nor does it require a particular arrangement of the pads in the case, by the person doing the packing.

Another advantage of the present arrangement over packing methods heretofore employed is that the cushioning effect is distributed throughout the stack and not concentrated primarily in the bottom cushion pad as before. Hence, there is less danger of egg breakage.

While in describing the invention, I have referred in detail to the form, arrangement, construction of the various parts employed, the same is to be considered only in the illustrative sense so that I do not wish to be limited thereto except as may be specifically pointed out in the appended claims.

I claim as my invention:

1. A packing material in the form of a cushion pad embodying therein a sheet-like body portion having a depressed marginal portion and parts formed as right angled rows of spaced apart unconnected depressions arranged at points coincident with the intersections of the strips of the cell forming fillers used with the pad, said depressions each having a bottom disposed in the plane of said marginal portion, other parts of said body portion being formed as article supporting seats arranged one within the area of each cell formed by the filler, each seat including a group of hollow upstanding projections arranged in spaced relation about a common central point for said group, and each projection being so formed in that side disposed radial with respect to said point as to provide an area of contact conforming to the associated part of the article to engage upon said projections.

2. A packing material in the form of a cushion pad embodying therein a sheet-like body portion having a depressed marginal portion and parts formed as right angled rows of spaced apart unconnected depressions arranged at points coincident with the intersection of the strips of the cell forming fillers used with the pad, said depressions each having a bottom disposed in the plane of said marginal portion, there being recesses in the margin of the body portion in line with said depressions and each having a bottom forming a continuation of said marginal portion, other parts of said body portion being formed as article supporting seats arranged one within the area of each cell formed by the filler, each seat including a group of hollow upstanding projections arranged in spaced relation about a common central point for said group, and each projection being so formed in that side disposed radial with respect to said point as to provide an area of contact conforming to the associated parts of the article to engage upon said projections.

WILLIAM J. DE REAMER.
